UNITED STATES PATENT OFFICE

137,460

DESIGN FOR A DIE FOR FORMING METAL SHEETS

John H. Engel, Escondido, Calif.

Application October 11, 1943, Serial No. 111,335

Term of patent 14 years

To all whom it may concern:

Be it known that I, John H. Engel, a citizen of the United States, residing at Escondido, in the county of San Diego and State of California, have invented a new, original, and ornamental Design for a Die for Forming Metal Sheets, of which the following is a specification, reference being had to

the accompanying drawing, forming part thereof.

The figure is an isometric view of a die for forming metal sheets showing my new design.

I claim:

The ornamental design for a die for forming metal sheets, as shown.

JOHN H. ENGEL.
